CLAIM

The ornamental design for a gallery device, as shown and described.

DESCRIPTION

FIG. 1 is a partially exploded view of a portion of a gallery device showing my new design;

FIG. 2 is a perspective view of the portion of the gallery device illustrated in FIG. 1;

FIG. 3 is a left side view of the portion of the gallery device illustrated in FIG. 2;

FIG. 4 is a front view of the portion of the gallery device illustrated in FIG. 2;

FIG. 5 is a right side view of the portion of the gallery device illustrated in FIG. 2;

FIG. 6 is a rear view of the portion of the gallery device illustrated in FIG. 2;

FIG. 7 is a top view of the portion of the gallery device illustrated in FIG. 2; and

FIG. 8 is a bottom view of the portion of the gallery device illustrated in FIG. 2.

The broken lines illustrate portions of the design that form no part of the claimed design.
